LOOM-TEMPLE.

No. 889,208.

Specification of Letters Patent.

Patented June 2, 1908.

Application filed October 7, 1907. Serial No. 396,129.

To all whom it may concern:

Be it known that we, JOHN V. CUNNIF and JAMES AINSWORTH, citizens of the United States, and residents of Fall River, 5 county of Bristol, State of Massachusetts, have invented an Improvement in Loom-Temples, of which the following description, in connection with the accompanying drawing, is a specification, like letters on the drawing representing like parts.

This invention has for its object the production of a novel loom-temple, so constructed and arranged that the rolls for engaging the body of the cloth present a yielding or elastic surface, which will firmly grip and hold the cloth stretched yet without marring or injuring it.

The novel features of our invention will be fully described in the subjoined specification 20 and particularly pointed out in the following claims.

Figure 1 is a face view of a loom-temple embodying our invention; Fig. 2 is a left hand side elevation of the temple head and a 25 part of the shank; Fig. 3 is a partial longitudinal section on the line 3—3, Fig. 2, to show more clearly the construction and arrangement of the rolls; Fig. 4 is a face view, partly broken out, of a modification to be 30 described.

Referring to the drawings, the temple head, comprising a pod B having a shank B' and heel B'', and the cap C connected with the pod by a screw c^x, may be of substantially usual construction, the ends of the cap 35 having opposite screw-studs c, c' on which the upper roll is mounted.

We provide yielding or elastic rolls to engage the body of the cloth, the surface of the 40 rolls being ribbed to afford a firm hold upon the cloth to maintain it stretched laterally, without marring or injuring it.

Referring to Figs. 1 and 3, the body-roll mounted in the cap is shown as made of a 45 coil of wire d of circular cross-section, wound to the proper diameter, with the spirals touching each other, and as shown in Fig. 3 the inner end of said roll is mounted upon a cylindrical head d', of wood or metal, centrally apertured to receive the end of the stud c', upon which said head rotates. At 50 its outer end the spirals of the coil are wound upon a cylindrical head d'', shown as an ex-

tension of a toothed selvage roll d³, made of wood and provided with teeth d⁴, and centrally apertured to loosely receive the stud c.

The selvage roll d³ is quite short, compared to the body roll, its object being to engage the cloth only at the selvage thereof, so that the teeth will not enter or injure the body of the cloth.

It will be seen that the surface of the body roll presents a spiral rib, the ribbing engaging and holding the body of the cloth, and as the greater part of the length of said roll is hollow it is adapted to yield or present an elastic surface. This gives a firm grip upon the cloth but without any liability to mark or injure it in the slightest, the selvage roll d³ and the body roll rotating in unison.

The heads d' and d'' are forced into the ends of the coil d and are held therein firmly by frictional engagement, the head d' having at its end a shoulder d^x, Figs. 1 and 3, against which abuts the end of the coil. The lower 75 body roll is also made as a close spiral coil e, of less diameter, as herein shown, and at its inner end it is rotatably supported by a stud b' in the end of the pod B, see Fig. 3.

At its outer end the wire of the spiral coil 80 is flattened and wound on a smaller diameter, at e', and is rotatably mounted on a stud b in the outer end of the pod. Upon this smaller coil e' we force a piece of rubber tubing e², leather or other suitable yielding 85 material, which is opposed to the toothed selvage roll d³, so that the points of the teeth can enter the same when they penetrate the selvage.

The opposed spirals of the body rolls tip 90 and hold the body of the cloth between them, while individual spirals of either roll have a slight movement transverse to their axis to accommodate inequalities in the thickness of the cloth, or the pressure due to 95 opposed spirals of the other roll.

In the modification shown in Fig. 4 we omit the toothed selvage roll, and mount the ends of the coil d^x on suitable heads f, f' which are rotatably mounted on the bearing 100 studs in the ends of the cap, the coil d^x *per se* being like the coil d and presenting a spirally-ribbed elastic and yielding surface. The lower roll in the modification is made by stretching a tube g of rubber over a series of 105 annular collars g' located at intervals on a

body g^2 , rotatably mounted at its ends in the pod, giving to the lower roll a ribbed elastic or yielding surface to engage the cloth.

In Fig. 4 one end, as g^3 , of the body is reduced to form a journal rotatably mounted in the inner end of the pod, and a screw stud g^4 at the other end of the pod is loosely inserted in an axial hole in the adjacent end of the body g^2 .

10 Having fully described our invention, what we claim as new and desire to secure by Letters Patent is:—

1. The combination, in a loom-temple having a roll to engage one face of the cloth, 15 of a coöperating roll composed of a flexible coil of wire having its spirals contacting with each other, and solid ends on which the ends of the coil are mounted.

2. In a loom-temple, a rotatably mounted, toothed selvage-roll, a connected roll for the body of the cloth, composed of a flexible coil of wire having its spirals contacting with

each other, a support for and on which is mounted the inner end of the flexible roll, and a coöperating roll for the body of the cloth.

3. In a loom-temple, a rotatable, toothed selvage roll having a cylindrical extension at its inner end, a coil of wire having its spirals contacting and mounted at its outer end on 30 said extension, a solid, rotatably supported head on which the inner end of the coil is mounted, the coil forming an elastic or yielding roll to engage the body of the cloth, and an opposed body-roll having a yielding surface.

In testimony whereof, we have signed our names to this specification, in the presence of two subscribing witnesses.

JOHN V. CUNNIFF.
JAMES AINSWORTH.
